UNITED STATES PATENT OFFICE.

FREDERICK LEUPOLD, OF PORTLAND, OREGON.

WINDING MACHINE FOR RECORDING PAPER.

Application filed October 19, 1922. Serial No. 595,553.

To all whom it may concern:

Be it known that I, FREDERICK LEUPOLD, a citizen of the United States, residing at Portland, in the county of Multnomah and State of Oregon, have invented a new and useful Winding Machine for Recording Paper, of which the following is a specification.

My invention relates to winding machines for recording paper, in which the factory roll, i. e. the roll of recording paper as furnished by the printing factory, is rotatably supported at one end of the machine, and rewound at the other end on the so-called supply roller, ready for use in a recording machine.

To a better understanding of this invention it may be mentioned that the factory roll contains a strip of paper possibly 1500 yards in length, whereas a recording machine requires only about 25 or 50 yards. Further, due to lateral swaying of the paper as the latter is sent through the printing roller, the longitudinal lines on the paper are never straight, but will sometimes deviate from a straight course by as much as one inch or more toward either side, while for recording purposes the lines must run absolutely true.

The objects of my invention are:

First, to rewind the paper in suitable lengths for a recording machine.

Second, to produce recording paper in rolls, with the lines running true for recording purposes.

Third, to produce an apparatus by means of which the recording paper can be rolled true for the purposes above mentioned.

Fourth, to produce an apparatus which is comparatively simple in construction and easy to manipulate.

Further objects and advantages will be pointed out at appropriate places in the specification and particularly in the appended claims.

I attain these objects with the mechanism illustrated in the accompanying drawings, in which:—

Fig. 1 is a plan view of the entire apparatus with the paper omitted.

Fig. 2 is a side elevation of Fig. 1.

Fig. 3 is a vertical, longitudinal section along the center line of Fig. 1, illustrating the course taken by the paper strip.

Fig. 4 is a detail of the rear pointer with a portion of the recording paper in the background.

Fig. 5 is a detail of the front pointer.

Fig. 6 is a portion of the supply roller, showing the core, the paper on the core and the washer.

Similar numerals refer to similar parts throughout the several views.

On each side there is a rail 1 resting on the legs 2. Both sides are held together by two stay bolts 3 at the bottom of the legs, one stay bolt 4 through the rails midways between the legs, one stay bolt 5 at the rear end of the rails, and one stay bolt 6 at the front end. Slidably mounted in the rails 1 above the stay bolt 5 are two rods 7 which are rigidly connected by a bridge 8. By means of a lever 9, which engages the bridge with the pin 10 (Fig. 3), said bridge and therewith the rods 7 can be shifted in lateral direction. One end of the lever is fulcrumed in the bracket 11, which latter is attached to the stay bolt 5, while the other end of the lever extends to the front end of the machine and finds a convenient resting place on the stay bolt 6. Attached to the rods 7 and movable therewith are the two brackets 12 and 13. The former usually retains a fixed position on the rods, the latter however, can be shifted according to the length of the factory roll 14 which is supported between the center points 15 and 16 in the brackets. From the factory roll the recording paper 17 is led over the idler 18 past the rear pointer 19 (Fig. 4).

The rear pointer is slidably attached to the angle bracket 20, in order to adjust itself to the altitude of the paper as the factory roll diminishes in size from a diameter of about 9 or 10 inches while new, to about 2 or 3 inches when the last layer is unwound. For auxiliary adjustment the leg of the angle bracket where it attaches to the side rail is slotted as indicated at 21. Thereafter the recording paper is led underneath the idler 22 and over the idler 23 to impart tension to the recording paper. For further tension the paper is led underneath the idler 24, and over the idler 25. At this point the paper is pressed upon by a rubber covered roller 25' which latter is guided in slots 26 in the side rails. By means of the rubber covered roller, the paper can be shifted to one side

or the other. To facilitate the shifting, a hand lever 27 is fulcrumed at 28 toward the left and at the outside of the rail. From the idler 25 the recording paper is led underneath the idler 29 and past the front pointer 30. This front pointer is mounted on a rod 31 between the side rails and is capable of adjustment in lateral direction for accurate setting on some particularly chosen line. From the idler 29 the paper is led on to the core 32 of the supply roller (the name supply roller refers to the ultimate function of supplying the paper in a recording machine).

15 The supply roller has one end mounted in the center point 33 on the bracket 34, and the latter is adjustably attached to the rods 35. The other end of the supply roller core has a hole 35' (Fig. 6), is supported in the center point 36, and carried around by a carrier pin 37 in the spindle 38. The spindle is mounted in the bearing 39 in the side rail and manipulated by means of the crank 40.

25 While the operator is turning the crank he must closely observe the front pointer and instantly correct any deviation of the paper from the true course by manipulating the hand lever 27. He must also cast an occasional glance at the rear pointer and correct any deviation from the true course shown there by shifting the factory roll by means of the lever 9.

35 After the supply roller has been wound with recording paper of the required length the uneven edges of the paper are cut smooth and true in a lathe, a washer 41 is placed over the core against the paper edges and the supply roller is ready to be packed 40 for shipment without danger that the alinement could accidentally be disturbed.

Having thus described my invention, it will be seen that my objects have been accomplished, and, though I have shown the 45 preferred form of construction, I reserve to myself the right to make minor changes providing I do not violate the spirit and principle of my invention.

50 So far as I am aware I am the first one to produce strips of recording paper in rolls, and I am therefore entitled to claim the machine per se, as well as the method and the product.

I claim:

55 1. In a winding machine for recording paper, the combination with a factory roll, of manually operated means to wind said paper on a supply roller, and means to observe the alinement of the longitudinal cross section lines irrespective of the marginal alinement of the paper itself.

65 2. In a winding machine for recording paper, the combination with a factory roll, of manually operated means to wind said paper on a supply roller and adjustable

means to check the true alinement of the longitudinal cross section lines irrespective of the marginal alinement of the paper itself.

3. In a winding machine for recording paper, the combination with a factory roll, of relatively movable supports for said factory roll, a supply roller rotated by a crank, a relatively movable support for one end of the supply roller, tension-producing idlers between the factory and supply roll, and means to check the true course of the paper over said idlers, said means comprising front and rear pointers. 70

4. In a winding machine for recording paper, the combination, of mechanism for winding said paper, with front and rear pointers for checking the true course of the paper, and means for correction of deviations from the true course. 80

5. In a winding machine for recording paper, the combination with a factory roll, of a supply roller, and means to wind the paper in true alinement on the supply roller, said means including normally stationary front and rear pointers, a crank adapted to rotate the supply roller, and an axially movable rubber covered roller extending throughout the width of the paper adjacent to the front pointer. 90

6. In a winding machine for recording paper, the combination with a factory roll rotatively mounted and having a relative movement in axial direction, of a supply roller, and means to wind the paper in true alinement on the supply roller, said means including adjustable front and rear pointers, and a lever cooperatively connected with the factory roll and extending to the front end of the machine. 100

7. In a winding machine for recording paper, the combination of two side rails, a factory roll mounted at one end of the side rails, a supply roller mounted at the other end of the side rails, idlers between the two side rails, a front pointer adjacent to the supply roller, and a rear pointer adjacent to the factory roll, both pointers checking the true alinement of the paper between the factory roll and the supply roller. 110

8. In the method of winding recording paper in true alinement, the steps of mounting the factory roll rotatably, of adjusting front and rear pointers to suitable longitudinal cross section lines on the paper, 120 of winding the paper manually on a supply roller core, and of checking the course of the paper between the factory roll and supply roller core by means of the pointers.

9. In the method of winding recording paper in true alinement, the steps of mounting the factory roll rotatably, of winding the paper manually on a supply roller core, of producing tension in the unwinding paper, and checking the course of 125 130

the paper by means of pointers disposed on the upper surface of said paper between the factory roll and the supply roller core.

10. In the method of winding strips of recording paper in true alinement, the steps of mounting the factory roll rotatably, of winding the paper manually on a supply roller core, of mounting a rear pointer over the paper adjacent to the factory roll, and 10 correcting the course of the paper by shifting the factory roll.

11. In the method of winding strips of recording paper in true alinement, the steps of mounting the factory roll rotatably, of 5 winding the paper manually on a supply roller core, of producing tension in the paper before reaching the supply roller core, of mounting a front pointer over the paper 15

adjacent to the supply roller core, and correcting the course of the paper immediately 20 preceding the supply roller core.

12. In the method of winding strips of recording paper in true alinement, the steps of winding said paper from a factory roll onto a supply roller, of producing tension 25 in the unwinding strip, of checking the course of the paper by means of a front and rear pointer, of shifting the factory roll laterally for correction with the rear pointer, and shifting the paper strip by means of a 30 rubber covered roller for correction with the front pointer.

Signed by me at Portland, Oregon, this 13th day of October, 1922.

FREDERICK LEUPOLD.
